MULTIPLE BUCK PRESSING MACHINE

Harry D. Forse, Anderson, Ind.

Application January 25, 1940, Serial No. 315,474

13 Claims. (Cl. 38—22)

This invention relates to a multiple buck, single head pressing machine.

One chief object of this invention is to provide a two-station pressing machine wherein at one station garments and the like may be pressed while other garments may be otherwise handled at a second station.

Another chief object of this invention is to provide a press capable of being operated by a single operator at a single station.

A further chief object of this invention is to provide a press capable of such operation and which occupies a small floor space.

The chief feature of the invention consists in providing in a pressing machine capable of accomplishing said objects, a pair of bucks, a single head successively associated therewith, the bucks in moving from one station to the other being always positioned upright for garment maintenance thereon, said bucks being cyclically movable from station to station about a horizontal axis, thereby distinguishing from a turret type press wherein the bucks are always coplanar and rotate about a vertical axis.

Other objects and features of the invention will be set forth more fully hereinafter.

The full nature of the invention will be understood from the accompanying drawings and the following description and claims.

In the drawings, Fig. 1 is a vertical sectional view of an embodiment of the invention, dotted lines indicating other positions of certain parts and the arrows designating the direction of rotation of the bucks from one station to another.

Fig. 2 is a front elevation of the bucks and connections and in a position midway between the operating stations.

Fig. 3 is an end view of the bucks as shown in Fig. 2.

Fig. 4 is an enlarged axial sectional view through one end of a buck pivotal support.

Fig. 5 is a similar view through the central pivotal support of the multiple buck arrangement.

Fig. 6 is a diagrammatic elevational view of a power "kick-off" mechanism for initiating buck revolution.

In Fig. 1, the numeral 10 indicates a frame structure upon which is suitably supported a pressing head 11 having a flexible steam supply line 12 suitably controlled by valves as at 13 and 14. The head is adjustably supported at 15 upon an arm structure 16 pivoted on frame 10 at 17. Upon extension 10a frame 10 is pivoted at 18 a rocker structure 19 connected at one end by

link 20 to the head supporting arm 16. The opposite end of the arm 19 mounts roller 21 arranged for cam operation, see cam 28.

The arm 16 is extended and upon the extended end 22 is secured a tension spring structure 23 which normally constrains the head 11 to elevated position—see dotted lines, Fig. 1. A pressure cylinder 24 is pivoted at 25 to frame 10. It includes a piston—not shown—mounted on rod 26 which supports at 27 a cam 28 pivoted at 17. The aforesaid is broadly disclosed in Patents No. 1,888,163; No. 2,053,366 and No. 2,062,745, so no further detailed description of the same or minor associated parts is believed necessary for an understanding of the present invention.

When there is no pressure in cylinder 24, spring 23 pulls down upon end 22 of arm 16 to raise the head supporting end upwardly into the dotted line position, see Fig. 1. When pressure is applied to cylinder 24, the piston therein raises with the rod 26, and tilts at 25 as required, and in such movement, cam 28 pivots on 17 and rotates counterclockwise and upwardly. In this movement roller 21 with arm 19 is rotated counterclockwise about pivot 18. Since link 20 connected arms 19 and 16, the latter, despite the constraint of spring 23, is caused to move downwardly from the dotted line to the full line position carrying with it the head 11 until the head engages buck 60, then properly and rigidly positioned for pressing engagement, the pressure applied for pressing being determined by several adjustments.

Pivotedly mounted at 29 on frame 10 is an upright or brace member 30 having the seat portion 31 and guide or cam portion 32. The casing, also of frame character, is indicated by numeral 33 and pivotedly supported thereby at 34 or any other suitable support is a treadle type lever 35 having the machine exposed, operator-operable, foot engageable portion 36. The opposite end of said lever is connected to link 37 pivotally connected at its opposite end to the pivotally connected adjacent ends of oppositely directed links 38 and 39 and as at 40. Link 38 at its opposite end is pivoted at 41 to brace 30. Spring 50 normally constrains lever 35 to elevated position, if the weight thereof be insufficient.

Pivotedly supported in frame 10 as at 42 is a lever 43 pivotally connected at 44 to the other end of link 39. When the treadle 36 is depressed, the link 37 elevates which forces the links 38—39 upwardly into inverted V-relation as shown by dotted lines in Fig. 1. This breaking of the toggle linkage draws brace member 30 rearwardly

and necessarily slightly downwardly, dotted lines to the right of the full lines in Fig. 1 indicating this position. This is the non-supporting and buck "clearing" position to which reference hereinafter will be had more fully.

A master valve housing structure 45 is carried by frame 10 and a flexible connection 46 connects the cylinder 24 thereto. The pressure supply 47 is controlled as at 48. The master valve housing includes two valves, the stems of which are indicated by numerals 51 and 52. Frame 10 carries spaced stops 49 and 53 which limit the oscillatory movement of member 43 about pivot 42, which oscillatory movement results from movement of link 39.

Member 43 has a contact head 54 of yielding character or yieldingly mounted and an extension 143 of member 43 mounts a similar structure 55 in similar manner. Therefore, in the movement of member 43 for pressure control of cylinder 24, these two valves (stems 51 and 52) are alternately operated for pressure and pressure release to permit raising and effect lowering of the head 11.

The stop 53 cooperates with member 43 to insure breaking or collapse of the toggle joint 38-39 when the treadle 36 is depressed and link 37 is elevated so that the brace 30 can move rearwardly, constrained thereto by gravity, rather than the toggle bodily moving forwardly while straightened, when the treadle is depressed. Hence, breakage of the toggle joint is assured and the brace is positively tilted rearwardly by treadle depression.

Reference now will be had more especially to Figs. 1 to 3, inclusive, wherein there is illustrated a pair of bucks 60, each supported by neck 61 on cross member structure 62 from which centrally depends arm 63 which mounts roller 64 on pivot 65. A shield 66 is secured to each buck assembly and moves therewith. It has a hand grip portion 67 to facilitate initiation of buck movement.

Secured to the opposite sides of the casing 33 and directed inwardly are the elongated bearings 68, see Fig. 2. Rotatably mounted therein is the shaft 69. Sleeve 70—see Fig. 5—may be provided or omitted, or replaced by an anti-friction structure of roller type.

Each end of the shaft 69 is longitudinally bored as at 71 and cross-bored as at 72. Each end thereof supports a connection 73 communicating with the conduit 74. The other end of the bore receives a tube 75 and the extreme end of the bore is enlarged as at 76 to receive a spring 77 bearing on face 78 at one end and on washer 79 at the other end. The latter bears on the packing 80. The extreme outer end of shaft 69 is threaded as at 81 to receive the retainer 82 through which projects tube 75. The outer end of the latter is threaded and is connected to the conduit 83 as by fitting 84. Thus, shaft 69 may rotate without rotation of tube 75 and the connection therebetween is leak-proof.

Referring to Figs. 1 and 2, it will be noted that adjacent the conduit 74 connected to the shaft at each end, there is secured an I-beam member 85 that rotates with the shaft 69. Each end of these beams terminates in a bearing 86, sleeved as at 87, see Fig. 4. Similar ends of opposite beams have these bearings 86 aligned and therein is mounted a shaft structure 88-89—see Fig. 4. Tube 88 is utilized to reduce weight and mass. Plugs 89 provide end strength and are bored L-shaped as at 90, the shorter length being transverse to the shaft axis and receiving fitting 109 to which conduit 110 is connected.

Since all four ends of the two shaft structures 88-89 are identical, further reference will be had only to that illustrated in Fig. 4. In a manner similar to that illustrated in Fig. 5, the coaxial length of bore 90 is enlarged to receive tube 91, and is further enlarged as at 92 to receive the spring 93 bearing at one end on face 94 and at its opposite end on washer 95. A closure 96 threaded to shaft 89 retains packing 97 and tube 91 extends through the closure and is connected by fitting 98 to tube 74. Thus, shaft structure 88-89 may remain stationary, relatively speaking, as to rotation, yet revolve as now set forth.

Secured to the interior face 100 of each bearing 68—see Fig. 5—are studs 101 which anchor and by means of spacing sleeves 102, the sprocket 103 with central opening 104 and peripheral teeth 105, the sprocket being spaced from the bearing 68 and adjacent the beam 85. Mounted on said sprocket is chain 106—see Figs. 1 to 3.

Rigid with each shaft 88-89 and on the free end thereof or exteriorly of the beam bearing, is sprocket 107—see Fig. 4 and Figs. 1 to 3—and the chain 106 meshes therewith. The sprockets 103 and 107 at each side of the machine are of coplanar alignment.

It will be apparent from the foregoing description and the drawings that when the adjacent hand grip portion 67 of the shield is tilted upwardly when brace 30 is released that the buck 60 immediately adjacent the operator with the garment thereon is moved upwardly and rearwardly in the direction of the arrow—see Fig. 1—and that by reason of the sprockets and chain mounting, the buck 60 will always maintain a position wherein the upper surface of the buck always is positioned upwardly. This is because sprocket 103 at each side of the rotatable structure is stationary and the chain 106 rolls thereon. Necessarily in the rotational movement, since the sprockets are of equal pitch and diameter, the shaft structure 88-89 rotate correspondingly in the first mentioned rotation which may be termed "revolution" so that the bucks always will be upwardly directed, irrespective of their revolved position and as illustrated by the dotted lines in Fig. 1.

In this connection it is to be noted that one of the conduits 84 at one end of the central shaft structure is an intake structure and the opposite one is an exhaust structure, and the respective conduits 74 from the respective intake or exhaust structures lead to the opposite ends of the revolvable shaft structures 88-89. The L-shaped bores 90 communicating with conduit 74, as aforesaid, connect by lines 110 and the extensions 108, shown dotted in Fig. 2, to the interior of the buck structure. One of these connections is of the steam supply type and the other is of the exhaust type. Thus, steam may be applied to each buck and exhausted therefrom. Thus, steam for heating purposes is always supplied as long as the valve 14 is open, it being understood that the line 13a is arranged to communicate with the supply line which may be the right hand conduit 84 in Fig. 2.

By referring to Fig. 1, there will be observed, immediately to the left of the member 30, a dotted line representation thereof and attention also is called to the dotted line representation to the right of the full line representation of the member 30.

When the treadle 36 is depressed, the brace structure 30 beneath the roller 64, carried by the depending arm 63, is retracted to the right hand

dotted line position. When this has been effected, it also is to be observed the head structure can be moved upwardly, as shown by the dotted lines in Fig. 1. Manual lifting on hand grip 67 then will cause the buck 60 adjacent thereto to revolve as shown by the arrows and will cause the right hand buck, heretofore associated with the head structure, to revolve downwardly and forwardly, being relieved from the engagement of brace portion 30. This rotation is continued and as the previously left hand positioned buck moves into the position almost that illustrated by the right hand full line buck in Fig. 1 and the treadle is released, the roller 64 engages the cam face 32, because upon release of the treadle, the member 30 has moved to its extreme counterclockwise tilted position—shown dotted in Fig. 1 and to the left in advance of the full line position—and in that subsequent contact the brace member 30 returns to the full line position shown in Fig. 1. This maintains a rigid bracing arrangement for the buck beneath the head structure 11 or in the pressing position. Thereupon the head structure 11 is lowered, as previously described, and pressing of the garment on the right hand buck 60 is effected. When this has been accomplished, the treadle is actuated for the aforesaid release, as described, and the bucks are again revolved manually.

If desired, power means may be provided for initially revolving the bucks and these may be treadle actuated or otherwise. In Fig. 6, there is diagrammatically illustrated such a "kick-off" mechanism. Shaft 69 supports, preferably centrally, two oppositely directed brackets or lugs 120, the same being transverse to the beams. Each lug is reduced as at 121 and pivotally supported at 122a in the recess is a bar 122 which engages a stop extension 123 on lug 120. Member 122 is normally constrained into stop engagement by spring 124 anchored to angle support 124a.

Adjacent the normal lower position assumed by such structure in its rotation, is a stationary cylinder 125 with bleed port 129 and piston 126 with the rod 126a extended therefrom as shown. Piston 126 is normally constrained by spring 127 toward the right. Pressure in opposition thereto is supplied as at 128 at the appropriate time to cause rod 126a to engage bar 122 to initiate clockwise revolution of the bucks. In this rotation of shaft 69, the approaching bar 122 engages stem 126a and the bar tilts counter-clockwise until it clears said member 126a. When thus clear it returns to original position and is positioned for subsequent piston rod engagement.

From the foregoing, therefore, it is obvious that the operator may stand immediately to the left of the foot treadle 36 and iron finish the garment, previously pressed, as to such portions as may require such supplementary attention, then remove the garment and place on the buck another garment for subsequent head pressing. This garment then is moved with the buck into the pressing position, as previously described, head pressed and then returned to the initial station for finishing and removal.

The advantage of this invention, as previously set forth, is that a single operator, during the head pressing operation, can finish-iron previously pressed garments, remove same from the forward buck and supply another garment thereto for subsequent pressing. In this way, the only limitation on production is that determinable by the head pressing cycle plus the time required

for revolution of the bucks from one position to another.

This invention also has the advantage that it occupies appreciably less floor space than that of a turret type, multiple buck press structure, wherein the turret rotates about a vertical axis and presents the several bucks in succession to one or more pressing stations.

The present invention furthermore has this advantage over the turret type structure mentioned, in that the supplementary ironing can be effected on the garment previously pressed immediately following pressing and thus the interval that is normally required for moving a particular buck from the pressing station to the unloading station in the turret type device is materially reduced and substantially eliminated, it being understood that such turret type devices usually include four or more horizontally rotatable bucks 20 per turret.

The other advantages previously mentioned hereinbefore are all effected by this invention.

It will be noted, see Figs. 1 and 6, that member 140 is mounted so as to be engaged by brace 30 when in fully retracted and non-supporting position. Member 140 is—see Fig. 6—constrained to closed valve position by spring 141. The valve is indicated at 142. Thus, operation of piston 126 is automatically controlled by brace movement so that revolution cannot be automatically initiated or attempted until the buck assembly 30 is freed from the locking brace 30.

It will be remembered the buck assembly arrangement may be manually revolved. Hence, in case the head jams, which would interfere with buck revolution, means is provided to prevent buck revolution until the head has sufficiently elevated to not interfere with buck movement.

One simple form of interlock includes member 160 pivoted to the frame at 162 and constrained to brace locking position by spring 163. The angular end 164 of member 160 is positioned adjacent brace 30. The other end of member 160 is connected by link 165 to the end of member 16—22. Thus, when member 16—22 is elevated (rotated clockwise) link 165 rotates member 160 counterclockwise in opposition to spring 163 and retracts the brace lock 164, permitting the brace 30 to move to its right hand dotted line position—see Fig. 1—which permits buck arrangement revolution. Any other suitable head associated brace lock may be employed in lieu of the foregoing.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. In a pressing machine, a single pressing head structure, a pair of buck structures, means connecting the bucks together for rotation about a fixed axis and rotation about the axes parallel thereto and offset therefrom, means coincident with each axis, and endless means simultaneously and operatively associated with all last mentioned means and arranged to maintain the bucks in the same relative position at all times.
2. In a pressing machine, a single pressing

head movable into and out of pressing position, a plurality of bucks successively movable into and out of pressing position, a single brace support means in juxtaposition to the pressing position for head juxtapositioned buck support for pressing purposes, and means operatively associated with the head and the brace means to cause sequential operation, said brace means being movable from the buck supporting position when the head is moved from pressing position to permit buck movement from the pressing position.

3. In a pressing machine, a single pressing head movable into and out of pressing position, a plurality of bucks successively movable into and out of pressing position, a single brace support means in juxtaposition to the pressing position for head juxtapositioned buck support for pressing purposes, means operatively associated with the head and the brace means to cause sequential operation, said brace means being movable from the buck supporting position when the head is moved from pressing position to permit buck movement from pressing position, and means arranged to move the buck upon completion of the pressing operation.

4. A pressing machine as defined by claim 1, wherein the pressing head is movable into and out of pressing position and each buck is successively movable into and out of pressing position, a single brace support means in juxtaposition to the pressing position for head juxtapositioned buck support for pressing purposes, and means operatively associated with the head and the brace means to cause sequential operation, said brace means being movable from buck supporting position when the head is moved from pressing position to permit head juxtapositioned buck movement from pressing position.

5. In a pressing machine, a single pressing head structure, a pair of buck structures, means connecting the bucks together for rotation about a fixed axis and rotation about other axes parallel thereto and offset therefrom, means coincident with all axes and arranged to maintain the bucks in the same relative position at all times, the pressing head is movable into and out of pressing position and each buck being successively movable into and out of pressing position, a single brace support means in juxtaposition to the pressing position for head juxtapositioned buck support for pressing purposes, means operatively associated with the head and the brace means to cause sequential operation, said brace means being movable from buck supporting position when the head is moved from pressing position to permit head juxtapositioned buck movement from pressing position, and means arranged to move the buck from pressing position upon completion of the pressing operation and brace means movement.

6. In a pressing machine, the combination of an overhead pressing head lowerable into pressing position, a plurality of interconnected bucks, arranged for rotation about a horizontal axis below and offset from the pressing position, means supporting each buck for automatic movement thereof in the aforesaid rotational movement to maintain said bucks in predetermined position regardless of rotational position, said bucks being successively movable into pressing position in timed relation to head movement into the same for pressing purposes, and brace means for stabilizing the buck in the pressing

position and movable in timed relation to buck movement for buck clearance.

7. In a pressing machine, the combination of an overhead pressing head lowerable into pressing position, a plurality of interconnected bucks, arranged for rotation about a horizontal axis below and offset from the pressing position, means supporting each buck for automatic movement thereof in the aforesaid rotational movement to maintain said bucks in predetermined position regardless of rotational position, said bucks being successively movable into pressing position in timed relation to head movement into the same for pressing purposes, and means operable in timed relation with head movement for initiating buck rotation when said head has moved sufficiently from the pressing position.

8. In a pressing machine, the combination of an overhead pressing head lowerable into pressing position, a plurality of interconnected bucks, arranged for rotation about a horizontal axis below and offset from the pressing position, means supporting each buck for automatic movement thereof in the aforesaid rotational movement to maintain said bucks in predetermined position regardless of rotational position, said bucks being successively movable into pressing position in timed relation to head movement into the same for pressing purposes, brace means for stabilizing the buck in the pressing position and movable in timed relation to buck movement for buck clearance, and means operable in timed relation with head movement for initiating buck rotation when said head has moved sufficiently from the pressing position.

9. In a pressing machine, including head moving means and movable buck bracing means, the combination of a single means for controlling both means, including a pair of pivotally connected links connected at the ends to said means, and a single manually operable member for actuating said links as a toggle arrangement.

10. In a pressing machine, including a rotatable shaft, means supporting same at the ends, a plurality of auxiliary supports parallel to the shaft and of lesser length, a corresponding number of radially directed spaced means carried by the shaft and adjacent its ends and rotatably supporting opposite ends of the auxiliary supports, and means operatively connecting all supports arranged for automatic support rotation in shaft rotation for maintaining the same relative positioning of the supports independent of movement incident to shaft rotation, the last mentioned means including a stationary sprocket coaxial with the shaft axis, a like sprocket rigid with each of the auxiliary supports and chain means interconnecting and meshing with all sprockets.

11. In a pressing machine, a single pressing head structure, a pair of buck structures, means connecting the bucks together for rotation about a fixed axis and rotation about other axes parallel thereto and offset therefrom, means coincident with all axes and arranged to maintain the bucks in the same relative position at all times, brace means in juxtaposition to the co-operating pressing positions of the head and buck structures for sustaining the buck structure in pressing position, means for moving said brace means into and out of sustaining position, means for revolving said buck structures, and means automatically operable in the movement of the brace means from sustaining position for actua-

tion of the revolving means upon brace means movement into non-sustaining position.

12. In combination, a plurality of bucks arranged for unit rotation, a pressing head movable into and out of buck pressing position, the paths of buck movement and head movement interfering, and buck movement preventing means automatically operable in head movement from buck pressing position when the interfering head path has been cleared by the head for permitting buck movement.

13. In a pressing machine, a single pressing head structure, a pair of buck structures, means connecting the bucks together for rotation about a fixed axis and rotation about the axes parallel thereto and offset therefrom, means coincident with all axes and arranged to maintain the bucks in the same relative position at all times, brace

means in juxtaposition to the cooperating press-ing positions of the head and buck structures for sustaining the buck structure in pressing position, means for moving said brace means into and out of sustaining position, means for revolving said buck structure, means automatically operable in the movement of the brace means from sustaining position for actuation of the revolving means upon brace means movement into non-sustaining position, and stop means for brace means association to prevent movement thereof for prevention of buck movement and automatically operable in the head movement after predetermined head movement has occurred, the buck and head each having paths of movement of which portions are of overlapping or interfering character.

HARRY D. FORSE.
